UNITED STATES PATENT OFFICE.

KARL ENGEL, OF ARLINGTON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

METHOD OF PREPARING SOLES.

1,281,539.

Specification of Letters Patent. Patented Oct. 15, 1918.

Application filed September 26, 1914. Serial No. 863,758.

To all whom it may concern:

Be it known that I, KARL ENGEL, a citizen of the United States, residing at Arlington, in the county of Middlesex and State of 5 Massachusetts, have invented certain Improvements in Methods of Preparing Soles, of which the following description, in connection with the accompanying drawings, is a specification, like reference characters on 10 the drawings indicating like parts in the several figures.

This invention relates to the manufacture of shoes and consists in certain improvements in methods of preparing soles. This 15 method is particularly applicable to the preparation of soles for use in the manufacture of single sole shoes, although it may also be employed to advantage in connection with outersoles or innersoles in making 20 welt or other double soled shoes. For the purpose of illustration the invention will be described with particular reference to its application to the manufacture of single sole shoes.

25 In the manufacture of shoes in which the upper is directly secured to a single sole, such as turn shoes and many stitch-down shoes and especially children's spring heel shoes, the use of the ordinary shank stiffener 30 as a separate article is prohibited because of the peculiar requirements which are essential to this type of shoe. The usual practice is, therefore, to conform the sole, while in temper, to the contour of the bottom 35 of the last and particularly to the arched shank portion of the last, the conformed shank portion of the sole tending to support the arch of the foot. It has been found, however, that the sole loses considerable of 40 the conformation imparted to it as the sole becomes dry and, also, when the shoe is subjected to wear the molded shank portion of the sole frequently breaks down, thereby 45 destroying the fit of the shoe and detracting considerably from its appearance.

I have discovered that a sole can be satisfactorily stiffened in the shank so as to maintain the shape imparted to it in the molding operation, and also can be given a 50 high degree of resilience which will cause it to tend to resume its molded shape after distortion during wear. This result I obtain in the illustrative use of the invention by applying a bonding and stiffening mate-

rial to the shank portion of the sole. In 55 the present instance the use of celluloid is illustrated. If celluloid is used it may advantageously be in the form of a thin sheet which is softened, as by alcohol or some other solvent for celluloid, and applied to 60 the mid portion of the shank of the sole or sole blank, preferably throughout the length of the shank, prior to the sole molding operation. The sole, being properly tempered, is then molded together with the sheet of 65 softened celluloid which latter is caused by the molding pressure to adhäre to and more or less permeate the sole and become united throughout its entire contacting face with the sole in such a manner as to be inseparable 70 therefrom during the use of the sole. The celluloid, including that which has permeated the shank of the sole, assumes during the molding operation the shape which is given to the sole by that operation so 75 as to maintain the shank resiliently in the desired shape. This invention, whether practised on the single sole of a turn or stitchdown shoe or on the outersole or the innersole of a double soled shoe, responds 80 to the requirements of practical use as to effective stiffening of the shoe shank and maintaining its molded conformation, as to durability and to resilience and, what is of prime importance in single sole work, these 85 results may be secured in the way herein-after particularly described without adding appreciably to the thickness of the sole or producing any objectionable protuberance thereon and without the use of fastening devices such as tacks or rivets. I have found, 90 in fact, that the sole may advantageously be reduced in thickness in the shank when this invention is employed, and thereby not only the appearance of the shoe be improved 95 as to flexibility but the resilience of the sole be actually increased.

When soles are molded prior to application to the shoe they must be worked in temper, the operation being carried on in 100 the stock-fitting room, and a quantity of soles are usually prepared at one time, many of which are allowed to dry before they are incorporated in the shoes. In drying they warp or twist and in such handling and 105 treatment as they may be subjected to before they dry, and after they have been re-tempered for the sole laying operation, the

molded soles are liable to become distorted, particularly in the shank portion. This invention is therefore of particular importance as an improvement in preparing soles 5 that are molded, before being laid although it is as well adapted for use in preparing unmolded soles, and the affixing or the final fitting of the stiffener to the sole if the sole is molded may advantageously be effected 10 simultaneously with the molding operation. In one of its aspects the invention consists in preparing a sole blank before incorporation of the sole in a shoe by stiffening the shank portion of the sole blank relatively 15 to the forepart with a shank stiffening element and then molding the shank portion of the sole blank to which the stiffening element is applied into the shape in which it is to be maintained by the shank stiffening element, all prior to assembling the sole with 20 the shoe. In another of its aspects the invention consists in assembling a sole blank and a moldable shank stiffener and then 25 simultaneously molding the sole and the stiffener together to the desired shape, prior to application of the prepared sole to a shoe.

The novel sole produced by the process hereinabove described is not herein claimed 30 but is claimed in my co-pending application Serial No. 60,335, filed Nov. 8, 1915, the said co-pending application being a division of this application.

The invention will now be described with 35 the aid of the accompanying drawings which illustrate one method by which it may be practised and also show a sole such as results from a practice of this method.

In said drawings:

40 Figure 1 is a perspective view showing a sole upon which the first step of the preferred order of steps for carrying out the invention has been performed.

Fig. 2 is a perspective view of the sole 45 showing the shank stiffener in applied position preparatory to the molding operation.

Fig. 3 is a perspective view of the sole after it has been molded and the stiffener or stiffener material affixed to it by being 50 caused more or less to permeate and closely to adhere to the shank portion of the sole.

I have employed this improved method in the manufacture of stitch-down shoes and will describe it as so used, although without 55 any intention that the invention shall be construed as limited to any particular class of soles or shoes.

In carrying out my invention in a preferred manner the sole blank 2 is first preferably reduced in thickness in the shank portion 3 of the sole by cutting it away from the flesh side as shown in Fig. 1, in order to make possible a thin appearing and flexible shank for the shoe. This split or skiving 65 is removed from the flesh side of the sole

from approximately the heel breast line to the ball line of the sole and across the entire width of the sole and is of substantially uniform thickness throughout so as to leave the reduced shank portion of the sole of substantially uniform thickness throughout and of less thickness than the adjacent portions of the sole as illustrated in Figs. 1 and 2 of the drawings. The sole is then "tempered," in which condition it is ordinarily placed 70 between dies and conformed to the contour of the bottom of the last or foot. In accordance with this invention the relatively thin shank portion 3 of the sole is treated with a bonding and stiffening material 75 which permeates more or less of the said portion of the sole and is of such a nature that when the sole is completed it will cause the sole to retain the form imparted to the sole in the molding operation and will also 80 possess such a degree of resilience as is desirable, particularly when used in the manufacture of children's shoes. I have found that celluloid or similar pyroxylin compounds, when employed in the manner set 85 forth by me, possesses the necessary properties for this purpose. In Fig. 2 is shown a relatively thin strip 5 of celluloid, which is preferably of the proper dimensions to cover all but the marginal edge portion of the 90 shank of the sole. This is applied to the flesh side of the sole, the marginal edges being left unaffected by the celluloid so as not to interfere with the channeling of the sole or with the stitching of the sole to the 95 upper. This strip 5 of celluloid is preferably treated, it may be on its lower surface only, with a suitable solvent which will partially dissolve and will soften the celluloid 100 and render it sufficiently plastic or semi-plastic to be conformed to the form given to the sole and also to penetrate into the leather and become firmly bonded to the fibers of the sole. While the celluloid, as well as the sole, is in the proper temper the work is 105 placed between suitable dies or otherwise molded to the proper conformation as shown in Fig. 3, during which molding of the sole the surface of the shank portion of the sole becomes more or less impregnated with the 110 celluloid and the celluloid becomes conformed to the curvatures of the shank portion 115 of the sole in which state the celluloid becomes set.

The sole thus formed is secured to the upper in any of the ordinary ways by usual fastening means in the further steps of manufacturing the shoe.

The use of celluloid or material having like properties as above described causes the shank portion of the sole to permanently retain the conformation imparted to it and thus provide a proper support for the arch of the foot. The resiliency produced by the celluloid in the shank of the shoe is partic- 120 125 130

ularly desirable in children's shoes. Moreover, the celluloid being firmly bonded to the leather fiber and absolutely impervious to moisture, either from the foot or from other sources, prevents the shank of the shoe from breaking down when the shoe is subjected to severe use. An important advantage to be noted is that the shank stiffening method practised by me leaves the inner surface of the sole substantially smooth, thereby being particularly adapted for use in the manufacture of shoes which do not have a slip sole or innersole, which condition has heretofore precluded the use of shank stiffening in this class of footwear.

Having described my invention, what I claim as new and desire to secure by Letters Patent of the United States is:—

1. That improvement in the art of making shoes which consists in applying a stiffening material to the shank portion of a sole, rendering said material temporarily plastic, molding the shank portion of the sole together with said plastic stiffening material to the desired shape and simultaneously impregnating the sole with said material and then allowing the stiffening material to harden while the sole is in its molded shape.

2. That improvement in methods of stiffening the shank portion of a sole which consists in applying a stiffening material to the inner side of the shank portion of the sole, rendering said material temporarily plastic, molding the shank portion of the sole and the stiffening material together and then allowing the stiffening material to harden.

3. That improvement in methods of stiffening the shank portion of a sole which consists in impregnating the shank portion of a sole with a material which may be caused to harden, molding said portion of the sole, and then causing the stiffening material to harden while the sole is in molded condition.

4. That improvement in methods of stiffening the shank portion of a sole which consists in applying a stiffening material to the mid-portion only of the inner surface of the shank portion of a sole, rendering said material plastic, molding the shank portion of the sole and the stiffening material together, and then allowing the stiffening material to harden.

5. That improvement in methods of stiffening the shank portion of a sole which consists in applying a sheet of celluloid to the shank portion of a sole, rendering said celluloid plastic, molding the shank portion of the sole and the celluloid together and causing the celluloid to permeate the shank portion of the sole and then allowing the celluloid to harden and become bonded to the fibers of the sole.

6. That improvement in the art of making shoes which consists in impregnating the shank portion of a sole with a stiffening

material in plastic condition and then allowing said material to harden while the shank portion of the sole is conformed to the longitudinal and transverse conformation of the shank portion of the last upon which the shoe is to be made.

7. That improvement in the art of making shoes which consists in stiffening the interior shank portion of a shoe sole by impregnating such portion only of the sole with a stiffening material in plastic condition and then allowing said material to harden with the entire shank portion of the sole conforming to the longitudinal and transverse curvatures of the shank portion of the last on which the shoe is to be made.

8. That improvement in the art of making shoes which consists in rendering the shank portion of the sole more responsive to the shank molding operation by removing from the shank portion of the sole a split of leather of substantially uniform thickness throughout the width of the shank and extending substantially from the heel breast line to the ball line so as to leave the shank portion of the sole of substantially less thickness than the adjacent portions of the sole.

9. That improvement in the art of making shoes which consists in improving the appearance of the shank portion of the shoe by removing from the flesh side of the shank portion of the sole a skiving which is of uniform thickness from approximately the heel breast line to the ball line and for a distance inwardly from each edge in excess of the material removed in the edge trimming operation whereby the thickness of the sole edge is substantially uniform throughout the shank and of substantially less thickness than the adjacent portions of the sole edge when the shoe is completed.

10. The herein described process which consists of assembling a sole and a moldable shank stiffener and then simultaneously molding the sole and shank stiffener to the desired shape prior to their being assembled in the shoe.

11. That improvement in methods of preparing soles which consists in assembling a sole blank and a shank stiffening element of normally resilient material, and then simultaneously molding said blank and shank stiffening element together to the required shape, prior to their being assembled in a shoe.

12. That improvement in methods of preparing soles which consists in cutting away a portion of a sole at the shank, applying a shank stiffening element to the reduced portion of the sole, and then molding the shank to the required shape, all prior to assembling the sole with the shoe.

13. That improvement in methods of preparing soles which consists in applying

- 45
5. moldable stiffening material to the shank portion of a sole, molding the shank portion of the sole, together with the said stiffening material, to the required shape, and 5. allowing the conformation imparted to the prepared sole to become permanent, prior to assembling the sole with a shoe.
14. That improvement in methods of preparing soles which consists in applying a 10 stiffening element to the shank portion of a sole and molding the shank portion of the sole to a predetermined conformation and simultaneously attaching the stiffening element to the sole.
15. 15. That improvement in methods of preparing soles which consists in applying a 15 stiffening element to the shank portion of a sole, and molding the shank portion of the sole, together with said stiffening element, 20 to the required shape, prior to their being assembled in a shoe.
16. That improvement in methods of preparing soles which consists in applying a 25 stiffening element of moldable material to the shank portion of a sole, and molding the shank portion of the sole, together with said stiffening element, to the required shape, prior to their being assembled in a shoe.
17. That improvement in methods of preparing soles which consists in forcing together a moldable sole and a shank stiffener and molding the soles to the longitudinal and transverse curvatures required to 30 fit the shank portion of a shoe, and removing the molding force while the stiffener acts to maintain the molded shape of the sole, all prior to assembling the sole with a shoe.
18. That improvement in methods of preparing soles which consists in forcing together a moldable sole and a shank stiffener and simultaneously molding the sole and affixing the stiffener permanently in such relation to the sole that it will assist in maintaining the molded shape of the shank portion of the sole.
19. That improvement in methods of preparing soles which consists in recessing a sole blank in the shank portion substantially from heel breast line to ball line, applying to the recessed portion of the sole a shank stiffener so related in thickness to the recess as to present no objectionable projection above the unrecessed portions of the sole and molding the sole with the stiffener in the recess to conform to the curvatures of the shank portion of the shoe for which the shoe is being prepared.
20. That improvement in methods of preparing soles for incorporation in shoes 60 which consists in cutting a piece of sole stock to the approximate size and shape of the shank and forepart of the sole, applying a shank stiffening element and then molding the shank portion of the sole into the shape 65 in which the previously applied shank stiffening element is to maintain the sole.
21. That improvement in methods of preparing soles for incorporation in shoes 70 which consists in stiffening the shank portion of a sole blank relatively to the forepart of the blank by attaching a shank stiffening element to the inner or flesh side of the sole blank and then shaping the said stiffening element into conformation with 75 the part of the sole blank to which it is applied, all prior to the assembling of the sole in a shoe.
- In testimony whereof I have signed my name to this specification in the presence 80 of two subscribing witnesses.
